(57) **CLAIM**

The ornamental design for a multifunctional hand tool, as shown and described.

DESCRIPTION

FIG. 1 is a front perspective view of a multifunctional hand tool, showing my new design;

FIG. 2 is a front perspective view thereof, with the blade cover detached and other components in their open configuration;

FIG. 3 is a rear perspective view thereof;

FIG. 4 is a rear perspective view thereof, with the blade cover detached and other components in their open configuration;

FIG. 5 is a front view thereof;

FIG. 6 is a rear view thereof;

FIG. 7 is a left side view thereof;

FIG. 8 is a right side view thereof;

FIG. 9 is an enlarged top plan view thereof; and,

FIG. 10 is an enlarged bottom plan view thereof.
